UNITED STATES PATENT OFFICE.

FRANKLIN G. HIRST, OF PHILADELPHIA, PENNSYLVANIA.

TEMPLE-ATTACHING DEVICE.

SPECIFICATION forming part of Letters Patent No. 707,109, dated August 19, 1902.

Application filed October 17, 1901. Serial No. 78,916. (No model.)

To all whom it may concern:

Be it known that I, FRANKLIN G. HIRST, a citizen of the United States, residing in the city and county of Philadelphia, State of Pennsylvania, have invented a new and useful Improvement in Temple-Attaching Devices for Eyeglasses, of which the following is a specification.

My invention consists of an improvement in temple-attaching devices for eyeglasses whereby the latter serve as spectacles.

It further consists of novel details of construction, all as will be hereinafter set forth and described.

15 Figure 1 represents a front elevation of a pair of eyeglasses with one temple-arm attached thereto. Fig. 2 represents a front elevation of the attaching means in detached position. Fig. 3 represents a top view of a 20 portion of a glass with the temple-attaching device in position, showing a portion of the temple-arm. Fig. 4 represents a top view, on a larger scale, of a temple-attaching device in a different position from that shown in Fig.

25 Fig. 5 represents a top view thereof, showing the parts in different position. Fig. 6 represents a perspective view of a portion of a temple-attaching device. Fig. 7 represents a side view thereof. Fig. 8 represents a plan 30 view of one of the straps in detached position. Fig. 9 represents a side elevation thereof. Fig. 10 represents a plan view of a portion of the temple-attaching device in detached position.

35 Similar letters of reference indicate corresponding parts in the figures.

Referring to the drawings, A designates an eyeglass, the same having the usual nose-piece and glasses or lenses, and as the same forms no part of the present invention it is 40 deemed unnecessary at this time to further explain the same.

B designates a temple-attaching device which consists of the body portion C, which 45 is provided with the lugs D, adapted to embrace the edge of the glass or lens, and secured to or forming part of the said body C is a strap or plate E, said body portion also carrying a spring-arm F, which is provided 50 with the nose or lug G. The strap E is provided with suitable material, such as rubber, on the inner face, and which is adapted to

bear against the side of the lens or glass. Suitably pivoted to the body portion is the movable strap H, which is likewise provided 55 with rubber or other suitable material and has an arm J extending from said strap. The latter, it will be seen, is pivoted opposite to the first-mentioned strap E. The strap H is provided with openings H' and H² to provide 60 for the adjustment of said strap relatively to different thickness of lenses, it being apparent that when a thin lens is employed a screw J' or its equivalent is inserted in the openings J² in the body portion C and the opening H' 65 in the strap H and that when a thick lens is employed the screw J' is inserted in the openings J² and H². The arm J is provided with a stop or lug J³, which abuts against the wall J⁴ of the body portion C and limits the 70 inward movement of the arm J, so as to prevent the extremity J⁵ of said arm from occupying a position out of the path of the shoulder M when the strap H is turned in the direction indicated by the arrows b in Figs. 3, 75 4, and 5.

K designates a temple-arm which is movably connected with the body portion C in the present instance by being pivoted to a plate L, which latter is pivoted to the body portion and is provided with the shoulders M and N, between which is adapted to rest the arm J. The plate L is provided with a recess P, which is adapted to receive a nose G of the spring-arm F, whereby said plate is 85 locked in position, it being noted that the temple-arm K is pivoted to the plate L for purposes to be hereinafter described.

The operation is as follows: When for any reason it is desired to have eyeglasses serve 90 as spectacles, the temple-arm K can be quickly supplied thereto in the following manner: The parts being in the position seen in Fig. 4 the shoulder N engages the arm J and causes the plate H to move away from the 95 plate E, permitting the insertion of a lens or glass therebetween. By now moving the temple-arm K to the proper position for operation or wearing the shoulder M contacts with the arm J and causes the same to assume the position seen in Fig. 3, and the lens will be held securely between the plates E and H, thus securing the arm K to the lens. The nose G of the spring-arm F meanwhile 100

enters the recess P in the plate L and locks the plate in that position, so that the temple-arm and connecting parts cannot be removed from the lens. In order to remove the temple-arm K from the eyeglass, the reverse operation is required, it being first, however, necessary to pull back the spring-arm F and release the nose G from the recess P, so that the plate L can be turned to cause the nose N to engage with the arm J, and thus separate the straps E and H. Should it, however, be desired to place the eyeglass and temple-arm in a case or receptacle without removing the temple-arm and connecting parts, the temple-arm, which is pivoted to the plate L, can be moved in the direction indicated by the arrow *a* in Fig. 5 and assume the position seen in dotted line in said figure, whereby the spectacles can be closed in a case, the straps, however, remaining secured to the lens, since the plate L is locked in position and prevents movement of the movable strap.

It will be apparent that various changes may be made by those skilled in the art which will come within the scope of my invention, and I do not therefore desire to be limited in every instance to the exact construction herein shown and described.

Having thus described my invention, what I claim as new, and desire to secure by Letters Patent, is—

1. In a device of the character described, straps movably connected to clamp the lens, a temple-bar connected with one of said straps and engaging the other strap to operate the same.

2. In a device of the character described, a body portion, a strap rigidly secured to the body portion, a second strap pivotally attached thereto, a temple-arm pivoted to said body portion, and means on said arm for operating said pivoted strap.

3. In a device of the character described, a body portion, a strap rigidly secured thereto, a strap pivoted to said body portion, an arm pivoted to said body portion, and shoulders on said arm adapted to contact with said pivoted strap for operating the same.

4. In a device of the character described, a body portion, a strap attached thereto, a second strap pivoted thereto, a spring-arm on said pivoted strap, a temple-arm pivoted to said body portion, and shoulders on said temple-arm adapted to engage said spring-arm.

5. In a device of the character described, a body portion, a strap secured thereto, a second strap pivotally attached to said body portion, a temple-bar pivoted to said body por-

tion, and means whereby said second-mentioned strap may be operated by said temple-bar.

6. In a device of the character described, a body portion, a strap secured thereto, a second strap pivotally attached to said body portion, and a temple-bar pivoted to said body portion and having means engaging with said second-mentioned strap to operate the same.

7. In a device of the character described, straps movably connected, to clamp the lens, a plate pivotally connected with one of said straps and engaging the other to operate the same, means for locking said plate in position and a temple-bar connected with said plate.

8. In a device of the character described, a body portion, a strap secured thereto, a second strap pivotally attached to said body portion, a plate pivoted to said body portion and engaging said second-mentioned strap to operate the same, and a temple-bar pivoted to said plate.

9. In a device of the character described, a body portion, a strap secured thereto, a second strap pivotally attached to said body portion, a plate pivoted to said body portion and engaging said second-mentioned strap to operate the same, a spring-arm adapted to engage said plate and lock the same in position and a temple-arm pivoted to said plate.

10. In a device of the character described, a body portion, a strap rigidly secured to said body portion, a second strap pivotally attached thereto, means for adjusting the position of said second-mentioned strap with respect to said body portion, a temple-arm pivoted to said body portion, and means on said arm for operating said pivoted strap.

11. In a device of the character described, a body portion, a strap attached thereto, a second strap pivoted thereto, a spring-arm on said pivoted strap, a temple-arm pivoted to said body portion, means on said temple-arm for operating said spring-arm and pivoted strap and a stop for limiting the movement of said spring-arm and pivoted strap.

12. In a device of the character described, straps movably connected to clamp the lens, a pivoted plate connected with one of said straps and engaging the other to operate the same, means for locking said plate in operative position and a temple-arm pivoted to said plate, whereby said temple-arm can be moved without moving said plate.
